UNITED STATES PATENT OFFICE.

HAROLD G. WARR, OF PARK RIDGE, ILLINOIS, ASSIGNOR TO THE P & M COMPANY, OF CHICAGO, ILLINOIS, A CORPORATION OF ILLINOIS.

RAIL-ANCHOR.

1,350,689.

Specification of Letters Patent. Patented Aug. 24, 1920.

Application filed September 27, 1919. Serial No. 326,854.

To all whom it may concern:

Be it known that I, HAROLD G. WARR, a citizen of the United States, residing at Park Ridge, in the county of Cook and 5 State of Illinois, have invented certain new and useful Improvements in Rail-Anchors, of which the following is a specification.

My invention relates to devices for preventing the longitudinal creep of railroad 10 rails and has for one of its objects to provide a novel and inexpensive rail anchor device which may be readily applied to the base flange of rails of different contour, which will firmly grip opposite edges of the 15 rail base with a biting hold during the presence of a creeping pressure on the rail and which will maintain its initial grip on the rail base by spring action.

The device of my invention preferably 20 consists of a spring yoke member which engages the rail base and a tie-abutting member which has an interlocking engagement with the spring yoke, so that the grip of the device on the rail is increased during 25 the creeping action of the rail. It has been customary, prior to my invention, to make the tie-abutting member of this general type of rail anchor in the form of a cast shoe which fits over one edge of the base flange 30 of the rail. The spring yoke used in connection with this form of shoe is formed at one end with a jaw to engage one edge of the rail base and at the other end with an enlargement which fits over and engages the 35 outer face of the shoe. With such a construction as this, a web forming part of the shoe, for example, that portion of the shoe which frictionally engages the vertical edge of the rail base, intervenes between the said 40 enlargement of the spring yoke and the edge of the rail base. In order to avoid a misfit of the anchor device on the rail base, this intervening web must necessarily be of uniform thickness. If the intervening web be 45 too thin, as often results from the shrinking of the casting, the spring yoke member will be too loose on the rail base, and if the web is of greater thickness than is intended, the application of the spring yoke is very 50 difficult. Further difficulty is experienced in properly applying these shoe members to oversized rails or standard rails having base flanges of different thickness, as it is not

always practical to force the shoe onto the base flange, the distance necessary to effect 55 a proper fit. In such event, if it is possible to apply the spring yoke, the yoke will be too tight to assume its desired diagonal position across the rail base. With my invention, I overcome the above mentioned 60 and other incidental objections to the general type of anchor above described, by providing the shoe member of my device with a recess which permits the enlargement 65 of the spring yoke member to directly engage and take a biting hold on the vertical edge of the rail instead of merely fitting over the shoe as is the case with the anchor of the type above described. By constructing the device so that the spring 70 yoke engages both edges of the rail base, it is obviously unnecessary that the shoe member fit the rail base accurately, thus avoiding the loss due to imperfectly formed castings, which under present practice are discarded, and at the same time permitting a 75 wider range of application of the device to rails of different standard contours.

My invention has for further objects such other novel construction and arrangement 80 of parts hereinafter described and claimed for carrying out the above stated objects and such other incidental objects as will appear from the following specification.

The invention is illustrated in a preferred 85 embodiment in the accompanying drawings, wherein—

Figure 1 is a plan view of a railroad rail showing an anchor device constructed in accordance with my invention applied to 90 the rail base,

Fig. 2 is a front view of the structure shown in Fig. 1, the rail being shown in section,

Fig. 3 is a view in perspective of the shoe 95 or tie-abutting member of my rail anchor device.

Fig. 4 is a plan view of the preferred form of spring yoke member employed in connection with the shoe member illustrated 100 in the preceding figure,

Fig. 5 is an end view of the spring yoke shown in Fig. 4, this view being taken from the right hand side of Fig. 4,

Fig. 6 is a side view in elevation illustrating the manner in which the spring yoke 105

member is sprung into operative engagement with the shoe member, and

Fig. 7 is a side view in elevation showing the spring yoke member in its interlocking 5 position with the shoe member.

Like characters of reference designate corresponding parts throughout the several figures of the drawings.

Referring to the drawings, 10 designates 10 a railroad rail and 11 one of the cross ties on which the rail is supported.

The device of my invention preferably consists of a spring yoke which embraces the base flange of the rail and a shoe member designated generally at 12, adapted to have an interlocking engagement with one end of the spring yoke; and a shoe member which preferably fits over one edge of the base flange of the rail and is formed with a 15 lip which frictionally engages the upper inclined surface of the rail base and with lower lips 14, 15 which frictionally engage the lower surface of the rail base. These lips are connected by a vertical web designated by 16, the inner surface 17 of which preferably, though not necessarily frictionally engages the vertical edge 18 of the rail base when the shoe is applied to the rail in its operating position. The lower lip 14 of 20 the shoe is formed with a downwardly extending flange 19 which provides a tie-abutting foot adapted to bear against one of the vertical faces of the tie 11. A portion of the vertical web 16 extends below the lower 25 lips 14, 15, as indicated at 20, so as to rigidify the tie-abutting flange 19. The web 16 of the shoe is preferably cut away as indicated at 21 to provide a recess adapted to receive one end of the spring yoke to provide 30 an interlocking connection hereinafter more specifically described. The forward edge of the downwardly projecting portion 20 of the vertical web 16 is formed with a ledge or shelf 23 adapted to provide a suitable 35 seat for the lower edge of the spring yoke member when the yoke member is in its operative position on the rail. The yoke member 22 of my device is preferably made of spring metal and is formed at one end 40 with a jaw portion 24, the upper lip 25 of which is curved in a direction toward the tie 11 and is adapted to bear with spring pressure on the upper inclined surface of the rail base. The other end of the spring 45 yoke 22 is formed with an enlargement 26 which engages the opposite edge of the rail base and when in operative position extends into the recess 21 as indicated in Figs. 1, 2 and 7. The portion of the yoke which extends under the base flange of the rail is 50 preferably given a slight set or twist as clearly indicated in Figs. 4 and 5. In Fig. 5 it will be noted that the enlargement 26 of the anchor stands at an angle with relation 55 to the jaw portion 24, the angularity of the

enlargement being in the direction opposite to the angularity of the upper lip 25 of the jaw end of the yoke. When applying my improved rail anchor device to its operative position, the shoe member 12 is fitted over one edge of the rail base in a position so that the flange 19 will bear against one of the vertical faces of a tie. The hook portion of the yoke is then fitted over the opposite edge of the rail base and the enlargement 26 positioned substantially as shown in Fig. 6 of the drawings. The enlargement 26 is then sprung in a direction toward the tie and slightly raised so that the upper end of the enlargement will enter the recessed portion 21, and the lower edge 28 of the yoke rest upon the shelf 23 of the web 20. This bending of the yoke from its normally twisted position as indicated in Fig. 6 to its operative position as shown in Fig. 7 is 85 preferably accomplished by means of a claw bar or wrench 27. The inner face of the wrench 27 is preferably provided with a lug 29 which bears upon a boss 30 projecting outwardly from the web 20 of the shoe. 90 This boss provides a suitable fulcrum for the wrench so that the maximum power may be applied to the spring yoke to apply it to the rail base. It will be seen that by subjecting the spring yoke member to a twisting strain during the application of the yoke to its operative position, the angular lip 25 of the jaw member 24 is forced downwardly so as to bear against the inclined surface of the rail base with spring pressure. The 100 tendency which the spring yoke has to return to the normal position from which it was sprung causes the enlarged portion 26 of the yoke to bear with spring pressure against the wall of the recess 21, as shown 105 in Figs. 1 and 7. This spring pressure is sufficient to maintain the anchor on the rail in its normal position during any retrograde movement of the rail or other disturbing influences such, for example, as the vibration 110 of the rail caused by the passing traffic. When the device is in its operative position the spring yoke 22 preferably extends diagonally across the rail base so that the edge 31 of the jaw 24 and the edge 32 of the enlargement 26 will take a biting hold on the rail during the presence of a creeping pressure. 115

I claim:

1. A rail anchor comprising a tie abutting member and a spring member adapted to engage opposite edges of the rail base and have an interlocking engagement with said tie abutting member. 120
2. A rail anchor comprising a tie abutting member which engages with one edge of a rail base and a spring member adapted to engage opposite edges of said base and have an interlocking engagement with said tie abutting member. 125

3. A rail anchor comprising a tie abutting member formed with a portion which fits over one edge of a rail base and a spring member adapted to engage opposite edges of said rail base and have an interlocking engagement with said tie abutting member. 5
4. A rail anchor comprising a tie abutting member formed with a shoe portion which fits over one edge of a rail base and 10 a spring member adapted to engage opposite edges of said rail base and have an interlocking engagement with said shoe portion of the tie abutting member.
5. A rail anchor comprising a shoe member which fits over one edge of the base flange of a rail, and a spring yoke member which interlocks with said shoe member and engages opposite edges of the rail base; said yoke being adapted to be strained in its 15 application to the rail whereby its initial grip on the rail is maintained by spring pressure.
6. A rail anchor comprising a shoe member which fits over one edge of the base flange of a rail and is provided with a recess which 20 exposes a portion of said base flange, and a yoke member formed with a jaw to engage the opposite edge of the rail base and having a portion adapted to engage the said exposed portion of said base. 25
7. A rail anchor comprising a shoe member which fits over one edge of the base flange of a rail and is provided with a recess which exposes a portion of said base flange, and a yoke member formed with a jaw to engage 30 the opposite edge of the rail base and having a portion adapted to engage the said exposed portion of said base; said yoke being formed with a slight twist whereby the yoke is strained in its application to the rail. 35
8. A rail anchor comprising a shoe member which fits over one edge of the base flange of a rail and is formed with a recess which exposes a portion of the edge of the rail base, and a yoke member having an interlocking engagement with the walls of said 40 recess and adapted to take a biting hold on opposite edges of the rail base.
9. A rail anchor comprising a shoe member which fits over one edge of the base flange of a rail, and a yoke member having an interlocking engagement with the shoe member and adapted to take a biting hold on opposite edges of the rail base. 50
10. A rail anchor comprising a shoe member which fits over one edge of a rail base and is formed with a recess, and a spring member engaging opposite edges of said rail base and adapted to be strained into interlocking engagement with the walls of said 55 recess.
11. A rail anchor comprising a shoe member which fits over one edge of a rail base and is formed with a recess, and a spring member engaging opposite edges of said rail base and having a projection which extends 60
- into said recess when the anchor is in operative position; said spring being formed with a twist whereby the same is subjected to a torsional strain when applied to the rail. 65
12. A rail anchor comprising a shoe member which fits over one edge of a rail base and is formed with a recess, and a spring member engaging opposite edges of said rail base and adapted to be strained into interlocking engagement with the walls of said recess whereby spring pressure is exerted against the upper and lower surfaces of the rail base. 70
13. A rail anchor comprising a shoe member and a spring yoke member which have an interlocking engagement with each other; the shoe member being formed with a tie-engaging portion and the spring yoke extending diagonally across the rail base and adapted to engage opposite edges of said base. 80
14. A rail anchor comprising a shoe member which fits over one edge of the rail base and is formed with a recess, and a spring member formed at one end with a jaw which engages one edge of the rail base and having an angularly disposed lip which engages the top surface of the base flange and formed at the other end with an enlargement which engages the opposite edge of the rail base and extends into said recess when the device is in operative position on the rail; said spring member being subjected to a torsional strain during its application to the rail whereby the said angular lip exerts a downward pressure against the inclined surface of the rail. 90
15. A rail anchor comprising a shoe member which fits over one edge of the rail base and is formed with a recess and with a ledge providing a seat, and a spring member formed at one end with a jaw which engages one edge of the rail base and has an angularly disposed lip which engages the top surface of the base flange and is formed at the other end with an enlargement which engages the opposite edge of the rail base, seats on said ledge and extends into said recess when the device is in operative position on the rail; said spring member being subjected to a torsional strain during its application to the rail whereby the said angular lip exerts a downward pressure against the inclined surface of the rail. 100
16. A rail anchor comprising in combination two members, one of which extends under and engages both edges of the base of the rail, and the other of which extends around one side of the base flange, bears against the tie and is held in place on the rail by the first specified member. 110
17. A rail anchor comprising in combination two members, one of which extends under and engages both edges of the base of the rail, and is formed of spring metal and 120
- 65

the other of which extends around one side of the base flange, bears against the tie and is held in place on the rail by the first specified member.

5 18. A rail anchor comprising a shoe member which fits over one edge of the base flange of the rail and is provided with a recess which exposes a portion of said base flange,

and a yoke member formed with a jaw to engage the opposite edge of the rail base and 10 having a portion adapted to engage said exposed portion of said base; said yoke being formed so that it is given a torsional strain in application to the rail.

HAROLD G. WARR.
